HEADSTONE

Forrest L. Cantrall, Benecia, Calif.

Application December 20, 1952, Serial No. 22,801

Term of patent 3½ years

(Cl. D79—2)

To all whom it may concern:

Be it known that I, Forrest L. Cantrall, a citizen of the United States of America, residing in the city of Benecia, in the county of Solano and State of California, have invented a new, original, and ornamental Design for a Headstone, of which the following is a specification, reference being had to the accompanying drawing, forming a part thereof.

I claim:

The ornamental design for a headstone, as shown.

FORREST L. CANTRALL.
